UNITED STATES PATENT OFFICE.

SAMUEL CHRISTOPHER McKEOWN, OF NEWARK, NEW JERSEY, ASSIGNOR TO SPLITDORF ELECTRICAL COMPANY, OF NEWARK, NEW JERSEY, A CORPORATION OF NEW JERSEY.

ELECTRIC-CIRCUIT-CONTROLLING DEVICE.

1,394,032.

Specification of Letters Patent.

Patented Oct. 18, 1921.

Application filed May 11, 1917. Serial No. 187,901.

To all whom it may concern:

Be it known that I, SAMUEL CHRISTOPHER McKEOWN, a citizen of the United States, residing at Newark, in the county of Essex 5 and State of New Jersey, have invented certain new and useful Improvements in Electric-Circuit-Controlling Devices, of which the following is a specification, reference being had to the accompanying drawing.

10 My invention relates to electric controlling devices whereby a circuit is made and broken automatically.

An object of my invention is to provide a mechanical means to automatically close 15 the circuit when the device in which the controlling mechanism is used, is in operation, and automatically open the circuit when the said device is at rest.

A further object of my invention is to 20 provide a mechanical arrangement employing frictionally engaged members, which may be separated from each other when the device reaches a pre-determined speed, thereby eliminating wear, while at the same time 25 the circuit is kept closed in the manner hereinafter described.

My invention is applicable for use in ignition systems for internal combustion engines where a timer supplied from a battery is 30 used, and in such a system my invention will prevent the waste of the battery current should the user forget to open the battery switch while the engine is at rest. While for the sake of illustration I show my invention used with an ignition system, it will be understood that I do not limit myself to this use, as the invention may be used in combination with any electric circuit or device where it is desirable to perform the 35 purpose which the said invention accomplishes.

In ignition systems, it is customary to 40 employ a timer mechanism comprising a pair of make and break contacts, together with suitable actuating means therefor, such as a rotating cam. In multi-cylinder engines a distributer is also employed, operating in synchronism with the timer mechanism. The timer contacts are placed in the 45 primary circuit, the distributer in the secondary circuit, and a switch is usually provided in the primary circuit for opening the same while the engine is at rest, thereby preventing the waste of battery. It is often 50 the case that the operator forgets to open 55

the switch, and in consequence battery current continues to flow through the timer and primary circuit, and waste of battery current occurs.

Many devices of the prior art show electric means for automatically opening the circuit while the engine is at rest. Such devices naturally require the expenditure of electrical energy for their operation. Many of them are comparatively sensitive in 60 operation and delicate in construction, and all of them have a "time element" or operating period during which they remain closed even after the engine is at rest.

My invention eliminates the foregoing objections in that it requires no electric current for its operation, is comparatively rugged in construction, and opens the circuit 65 immediately as soon as the engine stops.

There are other advantages hereinafter 70 fully described.

Referring to the drawings, Figure 1 is a view partly in section showing a timer and distributer equipped with my improved circuit controlling device. Fig. 2 is a diagrammatic view of the controlling device proper. Fig. 3 is a detailed view of part of the circuit controlling mechanism, and Fig. 4, a circuit diagram of the complete apparatus. Like figures of reference denote the same 80 parts wherever they are shown.

The numeral 1 indicates the driving shaft of the electric device, which may be operated in any suitable manner. In an ignition device such as shown this shaft 1 is 90 driven by the engine, and is rotated in fixed relation to the engine crank shaft. 2, denotes a fixed support which may be a part of the engine framework on which is mounted the plate 3, carrying the timer mechanism 95 of any suitable type such as the movable spring member 4 having a contact engaging the fixed contact 5. These make and break contacts are operated by the usual cam 6. A condenser 7 is connected across the contacts.

As the foregoing mechanism may be of any well known type, I do not describe the same in detail. Driven by the shaft 1 is the rotating finger 8, adapted to be connected at 100 9 to the secondary 10 of the induction coil and to distribute the high tension current by means of the terminals 11, 12, 13 and 14 to the spark plugs of the engine. The timer or make and break contacts 4 and 5 are con- 110

nected to the primary 15 of the induction coil, and to the battery 16 in series with contacts 17 and 18 hereinafter referred to as a circuit controlling means of the controlling mechanism 5 hereinafter described, the circuit arrangement being shown at Fig. 4. Secured to the shaft 1 is a shell 19, which incloses the segmentally divided ring 20, which is normally closed around the cone 21 by means 10 of three radially acting springs, two of which are shown at 22 and 23, these being positioned in apertures in the ring, two of which are shown at 24 and 25. Interposed between the inner surfaces of the ring and 15 the cam is a suitable frictional material, such as felt or cork indicated at 26, to give the required "creeping" action as herein-after described. Secured to the cone 21 and movable therewith is a flange 27 constituting a lever adapted to close the contacts 17 and 18, when the cone is rotated clockwise looking down from the top. The member 27 has an outwardly projecting nose 28, adapted to engage the movable contact 25 18 as shown. A back stop 29 is provided to limit backward rotation of the member 27. A spring 30 is positioned underneath 27 having an upward tension, so that when the ring 20 moves out of frictional engagement 30 with the cone 21, then the said cone may rise slightly, keeping contacts 17 and 18 closed, as herein-after described. The plate 31 on which the controlling mechanism is mounted is stationary at all times, being 35 part of the framework of the engine or other device, the same as the support 2. As the operation of the distributor is well understood, I do not describe the same, but will confine myself to a description of the 40 circuit controlling device comprising the circuit controlling means or contacts 17 and 18 and the actuating mechanism therefor. Shaft 1 being rotated, shell 19 rotates with it and also ring 20, the inner surfaces of 45 which frictionally engage cone 21, which tends to rotate, thereby causing nose 28 to press upon 18 which makes contact with 17, thereby closing the circuit through battery 16, timer contacts 4 and 5 and the primary 50 15 of the coil. The timer circuit being closed the timer functions in the ordinary way.

As the rotative speed of 1 increases, the divided ring 20 opens, due to centrifugal action, the pressure on cone 21 being thereby relieved the cone rises by reason of the spring 30, and this brings the nose 28 into engagement with the hooked portion of the back stop 29 shaped as shown, which keeps 55 contacts 17 and 18 closed in spite of the fact that cone 21 has been relieved from frictional engagement with the rotating element. As the speed decreases friction is re-established before the parts 28 and 29 unhook, so that the points 17 and 18 are held 60 65

together until the engine stops. As shaft 1 stops rotating, these contacts "creep" open, due to the peculiar "let go" action of the felt, cork or other frictional material at 26. The lowermost position of the core 21 is 70 limited by a shoulder on the plate 31.

While I have here illustrated and described simple and efficient means for carrying out the purpose of my invention, it will be understood that the same is not limited 75 to the details of construction as herein set forth, as it is obvious that the same may be varied without however departing from the scope of the appended claims:

1. The combination with an electric circuit of a pair of make and break contacts for periodically interrupting said circuit, actuating means for said contacts, normally open circuit controlling means in said circuit independent of said contacts and frictional means controlling the circuit and controlling means to close said circuit upon operation of the actuating means.

2. The combination with an electric circuit of a pair of make-and-break contacts 90 for periodically interrupting said circuit, actuating means therefor, circuit controlling means independent of said contacts, mechanism including frictionally engaged members closing said controlling means while 95 said actuating means is in operation, and means for opening said controlling means when said actuating means comes to rest.

3. The combination with an electric circuit of a periodic contact device, rotative 100 actuating means therefor including a shaft and cam, circuit controlling means independent of said contact device, adjacent said shaft, and mechanism actuated by said cam carrying shaft and including frictionally 105 engaged members for operating said circuit controlling means.

4. The combination with an electric circuit of a periodic contact device, rotative actuating means therefor including a shaft 110 and cam, circuit controlling means independent of said contact device, a member mounted on said cam carrying shaft, a second member frictionally engaging said first member, and means controlled by said second member for operating said controlling means.

5. The combination with an electric circuit of a timed contact device, rotative actuating means therefor including a shaft, 115 a member mounted on said shaft, a second member frictionally engaging said first member, means for opening and closing said circuit actuated by said second member, and means whereby said members are separated 120 by centrifugal force when said shaft reaches a predetermined speed.

6. The combination with an electric circuit of a timed contact device, rotative actuating means therefor including a shaft, 130

a friction member mounted to turn about said shaft, a second member upon said shaft movable therewith and adapted to frictionally engage said first member, and circuit controlling means operated by the movement of said first member.

7. The combination with an electric circuit of a timed contact device, rotative actuating means therefor including a shaft, a friction member mounted to turn about said shaft, a second member upon said shaft movable therewith and adapted to frictionally engage said first member, circuit controlling means adapted to be operated by the movement of said first member, and means for separating said members when said shaft reaches a predetermined speed.

8. The combination with an electric circuit of a contact device, rotative actuating means therefor including a vertical shaft, a friction member mounted to turn about said shaft, a second member fixed to said shaft and movable therewith and adapted to engage said first member, circuit controlling means adapted to be operated by said first member, means for separating said members at a predetermined rotative speed, and means for holding said circuit controlling means closed after the separation of said members during the ensuing rotation of said shaft above the predetermined speed, substantially as described.

9. In an electric circuit, a pair of con-

trolling contacts, actuating means for opening and closing said controlling contacts at predetermined speeds comprising frictionally engaging members for closing said contacts and means for holding said contacts closed and releasing said frictionally engaged members when said actuating means reaches a predetermined speed.

10. In an electric circuit, a pair of controlling contacts therefor, actuating means for opening and closing said contacts at predetermined speeds of said shaft, comprising a vertical shaft, a friction member driven with said shaft, a second friction member driven by said member and means operated by said second member for actuating said contacts.

11. In an electric circuit, a pair of controlling contacts therefor, actuating means for opening and closing said contacts at predetermined speeds of said shaft, comprising a vertical shaft, an annular divided ring carried by said shaft, a member within said ring and adapted to be frictionally engaged thereby and means operated by said last member for actuating said contacts.

In testimony whereof I hereunto affix my signature in the presence of two witnesses.

SAMUEL CHRISTOPHER McKEOWN.
